UNITED STATES PATENT OFFICE

161,088

CANASTA SCOREBOARD

Joseph D. Cacciarelli, Nutley, N. J.

Application March 16, 1950, Serial No. 8,566

Term of patent 14 years

(Cl. D34—5)

To all whom it may concern:

Be it known that I, Joseph D. Cacciarelli, a citizen of the United States of America and residing at 197 Raymond Avenue, Nutley, county of Essex, and State of New Jersey, have invented a new, original, and ornamental Design for Canasta Scoreboard, of which the following is a specification, reference being had to the accompanying drawing, forming a part thereof.

Fig. 1 is a top plan view of a canasta scoreboard, showing my new design; and

Fig. 2 is an edge view thereof.

I claim:

The ornamental design for a canasta scoreboard, substantially as shown.

JOSEPH D. CACCIARELLI.
